(57) **CLAIM**

The ornamental design for an air freshener device with drop-shaped gel container, as shown and described.

DESCRIPTION

FIG. 1 is a front and right side perspective view of a first embodiment of an air freshener device showing my new design;

FIG. 2 is a front plan view thereof, the rear plan view being substantially identical thereto; and,

FIG. 3 is a right side view thereof, the left side view being a mirror image thereof.

1 Claim, 1 Drawing Sheet
